US00D881250S

(12) **United States Design Patent** (10) Patent No.: **US D881,250 S**
(45) Date of Patent: ** Apr. 14, 2020

(54) **INTELLIGENCE ROBOT**

(71) Applicant: **BEIJING ORION STAR TECHNOLOGY CO., LTD.**, Beijing (CN)

(72) Inventors: **Hechun Yao**, Beijing (CN); **Xiaoying Liu**, Beijing (CN)

(73) Assignee: **BEIJING ORION STAR TECHNOLOGY CO., LTD.**, Beijing (CN)

(**) Term: **15 Years**

(21) Appl. No.: **29/664,004**

(22) Filed: **Sep. 20, 2018**

(30) **Foreign Application Priority Data**

Mar. 21, 2018 (CN) 2018 3 0106005
